UNITED STATES PATENT OFFICE.

HENRI GUÉRARD, OF LE HAVRE-GRAVILLE, FRANCE.

MEANS FOR PRODUCING LUMINOUS SHOWERS.

Application filed December 29, 1924, Serial No. 758,575, and in France January 8, 1924.

It is well known that certain hard bodies, when placed in contact with emery wheels in rapid rotation, will produce showers of sparks of a very brilliant nature by reason of the friction and wear of the material, and which can be compared for their attractiveness with the showers of fire produced by the known pyrotechnical pieces employed as luminous attractions.

10 The present invention relates to an apparatus for the production of showers of fire for luminous attractions or other purposes, consisting in the use of rapidly rotating emery wheels against which are placed in friction contact suitable pieces of steel, or more generally, of any common inexpensive substance or compound adapted to produce showers of sparks by wear or friction upon grinding wheels. In order to obtain the 15 desired results, I may apply against a rotating grinder a single piece of metal, thus producing a single shower of sparks, or a plurality of metal pieces mounted in a suitable supporting frame and producing a corresponding number of showers of sparks which are spaced around the said grinder. By a suitable rotation of the said frame about its centre, I am further enabled to obtain an 20 effect which is comparable with the effect produced by the piece of fireworks known as the sun-wheel.

In the appended drawings which are given by way of example:

Fig. 1 is a side view of an apparatus 25 whereby the method according to the invention may be carried into effect.

Fig. 2 is a section on the line A—A of Fig. 1.

Figs. 3 and 4 illustrate the effects which 30 can be obtained with the said apparatus, the frame carrying the metallic members being either stationary or rotatable.

The apparatus shown in the drawings 35 comprises a grinding wheel or disc 1 mounted upon a shaft 2 which is driven for example by an electric motor 3. A frame 4 which is mounted by easy friction upon the said shaft comprises for example, and as herein represented, six radial arms 5 having 40 mounted at the ends the members 6, sticks or blades, which are in friction contact with the said wheel. Upon the said frame is also mounted a toothed disc 7 engaging a pinion 8 which is driven either by the said motor 50 or by hand by means of the crank 9; by means of the said pinion, the said frame can

be rotated in either direction about the shaft 2.

The members 6, sticks or blades, which are made of steel or like material and are in 60 friction contact with the wheel 1, are mounted in the oblique holders 10, being slidable therein and adapted to be placed in contact with the edge or the side of the said grinding wheel, by means of the springs 11 which 65 are contained in the said holders. The latter are mounted upon the axles 12 which are engaged in the radial slots 13 formed in the ends of the arms 5 of the said frame, the axles being secured upon the said arms by 70 means of the nuts 14; this arrangement allows of regulating the inclination of the said holders relatively to the horizontal position, and of taking up the wear of the members 6 and of the said grinding wheel by the 75 displacement of the axles 12 in the slots 13.

When the grinding wheel is set in rotation, a shower of sparks will be produced at the point of contact of each of the members 6 with the grinding wheel, and the whole combination of the said showers of sparks will 80 produce the effect which is shown in Fig. 3; if the frame 4 is rotated about its centre, the showers of sparks will move with the frame, thus affording the effect which is shown in 85 Fig. 4.

The apparatus according to the invention, which enables the production of showers of sparks by means of suitable members of steel or like unexpensive material acting by friction upon grinding wheels, will produce 90 luminous effects of the most varied character, and these may obviously be combined with other effects obtained by known pyrotechnical methods, or by electrical or like means, for instance by electric illumination. The said luminous effects may be employed in theatres as well as for displays of fireworks, 95 for advertising purposes, or the like.

The apparatus producing the luminous displays according to the invention may be exposed to the weather or to dampness without inconvenience; it will not produce smoke or any disagreeable odour, and will offer no risk of fire or other accidents. Compared 100 with the known pyrotechnical devices, it will produce the desired luminous effect for a much greater length of time.

Obviously, the said invention, which has 110 for its object the obtainments of luminous effects for all desired purposes, which effects result from the production of showers of

sparks due to the friction or the wear of metallic or like members in contact with emery or like wheels, is not limited to the constructional forms hereinbefore set forth, 5 these being given solely by way of example of an apparatus or installation for the application of the said method. In particular, the emery wheels may be replaced by any other suitable devices.

10 Having now described my invention, what I claim as new and desire to secure by Letters Patent is:

15 1. An apparatus for the production of luminous showers for fireworks and the like, comprising in combination a motor, a grinding wheel secured on the shaft of said motor, a rotatable frame, means for supporting said frame coaxially with the motor shaft, at least one friction member carried by said

frame and adapted to engage with said grinding wheel, a rotary shaft operatively connected with said frame and means for rotating said shaft.

20 2. An apparatus for the production of luminous showers for fireworks and the like, comprising in combination a motor, a grinding wheel secured on the shaft of said motor, a rotatable frame, means for supporting said frame coaxially with the motor shaft, friction members adapted to engage with said 25 grinding wheel, means for yieldingly and adjustably supporting the friction members on the frame, a rotary shaft operatively connected with said frame and means for rotating said shaft.

30 35 In testimony whereof I have signed my name to this specification.

HENRI GUÉRARD.
